The ornamental design for a tire, as shown and described.

DESCRIPTION

FIG. 1 is a perspective view of a tire showing our new design, it being understood that the pattern repeats uniformly throughout the circumference of the tread;

FIG. 2 is a front elevation view thereof; and,

FIG. 3 is a side elevation view thereof; the opposite side being identical thereof.

The side walls and the text thereon form no part of the claimed design.

The broken line in the figure drawings represents unclaimed environment only and forms no part of the claimed design.
